TIMER

Filed June 11, 1937

UNITED STATES PATENT OFFICE

2,212,930

TIMER

Robert A. Cochrane, Los Angeles, Calif.

Application June 11, 1937, Serial No. 147,734

4 Claims. (Cl. 161—15)

This invention relates to a timer, and more particularly to a time recording apparatus adapted to indicate, as by a register or recorder, the integrated periods of time of operation of an internal combustion engine, or any other mechanism where there exists a pressure differential.

In some instances, especially in connection with automotive trucks, tractors and shovels, equipment including an internal combustion engine is used under a system in which pay for the use of the equipment is based upon the period of operation. Trucks for example may be thus rented; and since there may be extended periods of inactivity, an equitable system of charging for the use of such equipment is on the basis of the total times of activity.

It is one of the objects of this invention to provide a simple and reliable time recording apparatus especially adapted for this character of work.

It is another object of this invention to provide a recording time measuring apparatus that will function successfully under such extreme conditions of shock, vibration and dust as would reasonably be expected to cause interruption or damage to a clock works mechanism of conventional design.

As the readings of this device will often be used as the basis for the computation of earned rentals, and as the operator of the equipment to which it is attached, may be the renter of said equipment, it is also an object of this invention to provide a time recording apparatus for this class of service that is tamper proof and will require no winding, changing of charts nor electrical energy.

A further object of my invention is the provision of a time recording apparatus embodying any form of timer mechanism having a known and constant interval of operation, such as a dash pot, and which is set into operation by a partial vacuum supplied thereto from the suction side of an engine periodically through operation of a valve mechanism so as to cause uniform and periodical resetting of the timer mechanism, and a counter mechanism operable by the timer mechanism for recording the operations of the latter and in this manner recording the integrated periods of operation of the engine.

This invention possesses many other advantages, and has other objects which may be made more easily apparent from a consideration of one embodiment of the invention. For this purpose there is shown a form in the drawing accompanying and forming part of the present specifica-

cation. This form will now be described in detail, illustrating the general principles of the invention; but it is to be understood that this detailed description is not to be taken in a limiting sense, since the scope of this invention is best defined by the appended claims.

Referring to the drawing:

Figure 1 is a pictorial view of a time recording apparatus incorporating the invention, shown as enclosed in a housing, and as associated with an internal combustion engine, which is indicated diagrammatically;

Fig. 2 is a longitudinal sectional view of the apparatus shown in Fig. 1;

Fig. 3 is a transverse sectional view taken along plane 2—3 of Fig. 2;

Fig. 4 is an enlarged sectional view taken along the plane 4—4 of Fig. 3;

Fig. 5 is a fragmentary view similar to Fig. 4, but with some of the parts in section;

Fig. 6 is a sectional view taken along plane 6—6 of Fig. 4;

Fig. 7 is a sectional view taken along plane 7—7 of Fig. 4; and

Fig. 8 is a sectional view taken along plane 8—8 of Fig. 4.

The apparatus shown in Fig. 1 is arranged to indicate or record or register the integrated time intervals of operation of the internal combustion engine 1, or other mechanism that develops a pressure differential. This internal combustion engine 1 may be installed on a truck or utilized for other purposes. It is shown as provided with an intake manifold 2, forming a part of the intake passages to the cylinders of the engine 1.

The timer mechanism, shown in greater detail in Figs. 2 to 8 inclusive, is shown in Fig. 1 as in a locked or sealed box or housing 3, which may be appropriately supported at or near the engine 1. Although this housing 3 may be locked or sealed to ensure against unauthorized tampering, it is provided with a viewing window 4 through which a register, indicator, or recorder enclosed within the housing 3 may be viewed. In the present instance a register mechanism 5 is utilized, and is shown in Figs. 2 and 3 as a counter mechanism having an actuating oscillatable arm 6. Its dial is placed below the window 4, which may be formed of a glass plate held by a frame 7 to the lower side of the top of housing 3.

The timer mechanism must have a known and substantially constant operating interval, that is, that interval between the setting of the mechanism into operation and the cessation in operation. Such a timer mechanism suitable for the

purpose is a dash pot in which the operating interval of the piston in its retarded stroke within the cylinder is known and constant.

Hence, as a timer mechanism I employ a dash pot 4, shown in Fig. 2, as comprising a piston structure 8 operating within a cylinder structure 9. Upon the bottom 10 of the housing 3 the two cylinder heads 11 and 12 may be supported, as by the feet 17. Between these two cylinder heads there is clamped the cylinder proper 13. The construction is made air tight at the right hand end of the cylinder by the aid of an annular gasket 14. The assembly of the heads 11 and 12 with the cylinder proper 13 is effected by the aid of a plurality of through bolts 15 passing through ears 16 formed on the cylinder heads 11 and 12.

The cylinder head 11 is provided with a central guide boss 18, through which the piston stem 19 extends. The piston structure 8 is supported on the stem 19. It is shown as including a cup leather 20 clamped between the discs 21 and 22. This clamping is effected by the aid of a nut 23 engaging the threaded reduced portion 24 of the stem 19. The shoulder formed at the left hand end of the reduced portion 24 serves as an abutment for the piston structure 8, so as to make it possible to tighten the structure 8 thereon.

The counter or register 5 is adapted to be operated by the aid of a projection 25, shown as formed integrally with an arm 26 fastened to the left hand end of the stem 19. As the piston structure 8 moves inwardly with respect to the cylinder 13, the projection 25 strikes the arm 6 and causes the register 5 to record the number of inward reciprocations. The register 5 and the operating arm 6 are so arranged that movement of the piston structure 8 outwardly, that is, toward the left, will cause the arm 6 to rotate 40 in a clockwise direction without operating the register 5. In this way each complete cycle of piston operations causes one operative oscillation only of the arm 6.

The numbers on the counter 5 may be arranged 45 so as to indicate directly the hours and tenths of hours comprised by integration of the intervals of operation of the mechanism 1. Thus a complete reciprocation may be so timed as to occur in six minutes, that is, once in one-tenth of an hour. Accordingly the right hand figure appearing on indicator 5 will represent tenths of hours; and the remaining figures will represent the whole number of hours.

In the present instance the register 5 is shown 55 as conveniently supported upon a bracket 27 fastened to the cylinder head 11.

Connections are provided from the interior chamber of cylinder structure 9 to the intake manifold 2. Thus there is a conduit 28 which 60 is connected at one end 29 into the manifold 2. This connection may be sealed against removal as by appropriate seal 30. The other end of connection 28 extends to a nipple structure 31 supported on the side wall 32 of the housing 3. 65 This nipple structure is engaged by a nut 33 carried by the end of the conduit 28 and sealed against removal, as by a wire 34 and seal 35.

The inside end of the nipple structure 31 may be similarly connected to a connection 36 which 70 leads to a valve structure to be described in detail hereinafter. From the valve structure the connection proceeds, as by aid of connection 47, to the nipple 37 attached to the cylinder head 12, and in communication with the cylinder 75 chamber.

When the valve mechanism between connections 36 and 47 is open, the partial vacuum existing in manifold 2 is effective within the cylinder space, and causes the piston structure 8 to move inwardly, that is, toward the right as 5 viewed in Fig. 2. However, upon approaching the extremity of its stroke, the piston structure 8 and valve stem 19 are so arranged that they actuate the valve means to disconnect the source of vacuum 2, and the piston 8 is moved outwardly 10 or toward the left. This is accomplished by the aid of a compression spring 38 located within the cylinder space and which had been compressed by the inward movement of the piston structure 8. The motion of the piston structure 8 inwardly is quite rapid and the spring 38 is so designed that the pressure effects created by the partial vacuum within the cylinder space is sufficient under any condition of engine operation to overcome the spring 38. However, when the 20 partial vacuum is destroyed, the piston structure 8 is caused to move slowly toward the left or outwardly. This is accomplished by providing a restricted vent from the cylinder space so that it is only at a slow rate that the vacuum is destroyed in the cylinder space.

This restricted vent is provided by the aid of a needle valve structure 39 fastened in the head 12. The atmospheric vent or connection is indicated at 40. The size of the vent is controllable by a needle valve closure operated by the thumb screw 41 engaging threads within the body of the structure 39. It may be held in adjusted position as by the aid of the check nut 42. Thus by accurate adjustment of the thumb screw 42, the period required for the piston structure 8 to move to its extreme outward position may be controlled. Of course, the vent 40 is so greatly restricted that it does not interfere appreciably with the creation of the partial vacuum within the cylinder space, when the valve mechanism connects the cylinder space with the source of vacuum 2. In order to relieve any pressure differential on the left of piston 8, the head 11 may be appropriately vented.

Upon arrival of the piston structure 8 near its extreme outward position, the valve mechanism is actuated to reconnect the cylinder space to the manifold 2, and the cycle of operations is repeated. In order that the interior of housing 3 may at all times be at atmospheric pressures, a dust-proof opening is provided in the wall 32. This opening is formed by a small cup-like structure 43 having apertures therein and filled with dust trapping material, such as oil soaked snarled wire. It may be covered over by an apertured plate 44. Thus a breather is provided for the interior of the housing or casing 3 which is preferably otherwise air-tight.

The control valve mechanism is illustrated 60 most clearly in Figs. 4 to 8 inclusive. Thus in Figs. 4 and 6, the connection 36 is shown as leading to aperture 46 within a block 45. The connection 47 from the cylinder nipple 37 is similarly connected to another aperture 48 within the block 45.

The connection between apertures 46 and 48 is controlled by a slide valve plate 49. This valve plate 49 has a depending boss 50, provided with a recess 51 wide enough to connect the two apertures 46 and 48 when the plate 49 is in the position of Fig. 6. Accordingly, for this position the valve mechanism is open and the partial vacuum is effective within the cylinder space.

However, the slide plate 49, if moved toward 75

the left as viewed in Fig. 6, or downwardly as viewed in Fig. 4, will bring the recess 51 out of communication with the aperture 46. The plate 49 is guided as by the aid of a pair of screws 52 and 53 passing through slots, such as 54 and 55 in the plate 49. The screws 52 and 53 are fastened into the bar 45. Compression springs 56 may be interposed between the heads of screws 52, 53 and the top of plate 49, so as to ensure substantially air-tight fit between the boss 50 and the top of bar 45.

The plate 49 is adapted to be quickly snapped to open and to closed position by an over-center mechanism to be later described. It is shown as joined as by the aid of its upstanding ear 57 (Figs. 4 and 6) to a corresponding ear 58 on the top plate 59 of a movable carriage structure to be hereinafter described.

This movable carriage structure as shown most clearly in Figs. 7 and 8, includes, in addition to its top plate 59, a lower plate 60. The two plates are held in spaced relation at one end by the aid of a pair of spacer bushings 61 (Figs. 5 and 7) through which pass the fastening screws 62. At the opposite end the plates 59 and 60 of the carriage structure are held in spaced relation by carriage guide rollers 63, the pivot pin 64 of which may be fastened as by riveting to the plates 59 and 60.

This carriage structure is guided for movement to control the valve mechanism by the aid of a stationary guide structure. This guide structure is shown most clearly in Figs. 4, 5, 7 and 8. It comprises a bottom plate 65 supported in spaced relation to the bottom wall 10 of the casing. It also has a top plate 66 which may be connected to the bottom plate 65 by the vertical wall 67 (Fig. 5). These top and bottom plates 65 and 66 are embraced between the top and bottom plates 59 and 60 of the carriage structure. The carriage structure is intended to slide over these spaced plates 65 and 66.

Limits are imposed to the extent of slide of the carriage to correspond with the opening and closing of the valve mechanism. These limits may be provided by the transverse bar stops 68 joined to the plates 65 and 66. In Fig. 8, the carriage structure 59-60 is shown as in its extreme right hand position against the right hand stops 68; this corresponds to the uppermost position of Fig. 4, the valve mechanism being open. Upon movement of the carriage longitudinally to cause it to contact with the left hand stops 68' (Fig. 8) the valve mechanism is closed.

The snap-over action between these two extreme positions is provided by the aid of a longitudinally movable bar 69 slidably guided between the upper and lower stationary plates 66 and 65. This bar 69 as shown most clearly in Fig. 8, may be provided with slots 70 and 71 through which pass the guide screws 72, to constrain the movement of the bar 69 in a direction parallel to the movement of the valve plate 49. The carriage rollers 63 engage one edge of the bar 69. The bar 69 is also provided with a pair of tapered notches 73 and 74 at one edge thereof. Between these notches is formed a tooth 75. A roller 76 supported by the carriage 59-60 is adapted to engage within either one or the other 70 of the notches 74 and 75. This roller is also carried by the carriage structure 59-61. Roller 76 is provided with a pivot pin 77 extending through slots 78 and 79 in the upper and lower plates of the carriage. Furthermore, the roller 75 76 is urged resiliently into the corresponding

notch by the aid of the tension springs 80 and 81. These rollers 63 and 76 thus form a convenient guide for properly defining the movement of the carriage with respect to bar 69. One end of each of these springs is anchored to the corresponding end of the pivot pin 77. The other end of each of the springs is anchored to a screw 82 or 83 supported on the flanges 84 or 85, respectively formed on the top plate 59 and bottom plate 60 of the carriage structure.

It is apparent that when the bar 69 is moved upwardly as viewed in Figs. 4 and 5, the springs 80 and 81 will first be stretched until the roller 76 has moved completely out of the notch 73, up to the apex of tooth 75; and thereafter the roller will be urged by the springs 80 and 81 quickly into the lower notch 74. Due to the slope of the walls of the notch 74, the carriage as a whole will be moved downwardly as viewed in Figs. 4 and 5, or toward the left as viewed in Fig. 8. This causes a corresponding movement of valve plate 49, causing the valve mechanism to close.

Conversely, when the valve mechanism is closed, a movement of the bar 69 downwardly will cause eventually a corresponding quick motion of carriage 59-60 upwardly to open the valve. The vertical wall 67 is appropriately slotted as indicated at 86 (Fig. 5) to permit the roller 76 to contact with the bar 69.

The reciprocations of the bar 69 are controlled by motion of the piston stem 19 and the arm 26 attached thereto. Thus the bar 69 is provided with an upturned flange 87 (Figs. 4 and 8). To this flange is attached a threaded rod 88. This threaded rod 88 carries the adjustable abutments, such as the nuts 89 and 90. The arm 26 is apertured so that rod 88 may pass therethrough. Between these nuts 89 and 90 the arm 26 is arranged to travel. When the arm 26 is carried sufficiently toward the left as viewed in Fig. 2, it contacts with the abutment 90 to draw the bar 69 downwardly as viewed in Fig. 4, and to place the bar in valve opening position, as illustrated in Fig. 6. However, as soon as this is accomplished, the partial vacuum is immediately effective and the piston structure 8 moves rapidly toward the right as viewed in Fig. 2. Near the extremity of its motion, the arm 26 contacts with the other abutment 89, and urges the bar 69 upwardly as viewed in Fig. 4. This upward motion as heretofore explained, causes the carriage structure and the valve plate 49 rapidly to snap downwardly to valve closing position. Thereafter the cycle is repeated, during the entire interval of engine operation.

The operating interval of the dash pot, that is, the time during which the piston structure 8 and its associated stem 19 moves outwardly of the piston is accurately controllable by the aid of the adjustable vent 40, and thus the operating interval of the dash pot can be timed and made constant. The timing function can thus be accurately calibrated.

The mode of operation of the system is quite apparent from the foregoing. With the bar 69 in valve opening position, the recess 51 in plate 49 effects the vacuum connection from the manifold 2 to the cylinder space. Immediately the piston structure 8 and valve stem 19 move rapidly toward the right as viewed in Fig. 2, compressing the spring 38. Near the extremity of this motion, the arm 26 contacts the abutment 89. Thereafter the bar 69 is moved upwardly as viewed in Figs. 4 and 5 or to the right as viewed in Fig. 8. The roller 76 of the carriage 59-60 75

is urged outwardly of the notch 73 by this upward movement. As soon as this roller passes the apex of the tooth 75, the carriage structure is rapidly moved in a downward direction. This carriage structure carried with it the plate 49, and the valve mechanism is closed. Thereafter the partial vacuum is no longer effective to hold the piston structure 8 in its inward position, the vacuum being gradually destroyed by the vent 40. The spring 39 urges the piston structure 8 outwardly at a slow rate. At the extremity of this outward movement, the arm 26 contacts the abutment 90 and thereafter pulls the bar 69 downwardly to the position illustrated in the drawing. This downward movement of bar 69 eventually causes the roller 76 to snap upwardly into the position illustrated in Fig. 5, and the valve plate 49 moves to the opened position shown in Fig. 6. The cycle is then repeated as often as permitted during operation of engine 1. From the preceding operation of the time recording mechanism, it will be clear that with each cycle of operation, the piston of the dash pot is reset or moved to the right hand end of the cylinder under each power impulse produced by the partial vacuum admitted to the cylinder, and that although there is a slight variation in the power of the impulses due to the variation in the degree of vacuum produced in the intake manifold, such variation in power of the impulses is negligible for all practical purposes, as it does not affect the accuracy of the mechanism required to time and record the integrated periods of operation of the engine. This is due to the fact that the dash pot is so designed that even the lowest degree of vacuum produced in the intake manifold is sufficient to rapidly move the piston to set position; and what slight variation may occur in this movement is negligible as compared to the slow movement of the piston to unset position. Tests conducted with an apparatus constructed in accordance with my invention and under extreme conditions of suction fluctuation showed that where the dash pot required six minutes to complete one cycle of operation, 357 seconds were consumed by the piston in its movement to unset position, while only three seconds were consumed by the piston in its movement back to set position. In other words, the time consumed in the movement of the piston

to set and unset positions was in the ratio of 119 to 1.

What is claimed is:

1. In a time registering apparatus; a dash pot including a vented cylinder, a piston, and a spring for slowly moving the piston in one direction in the cylinder to an unset position; means adapted for connection to the suction side of an engine and communicating with said cylinder to cause the resultant vacuum to rapidly move said piston to a set position against the tension of said spring; and a valve mechanism operable by movement of said piston for disconnecting the cylinder from the engine upon the piston reaching set position. 15
2. In an apparatus for registering the periods of operation of an engine; a dash pot having a cylinder with a restricted air vent, and a piston; means adapted to control the connection of the cylinder to the suction side of an engine to cause the piston to move rapidly in one direction in the cylinder; means for yieldably urging the piston in the opposite direction in the cylinder to cause relatively slow movement thereof under the action of said vent; and means for actuating the controlling means to establish the connection between the engine and the cylinder when the piston is moved to a predetermined position by said urging means, and to cause a disconnection between the cylinder and engine when the piston is moved by the engine suction to another position. 25
3. In an apparatus for measuring the periods of time of operation of any engine providing a source of pressure differential; means for converting the pressure differential into periodical power impulses; and a dash pot correlated to said means so as to be periodically reset by the power impulses. 35
4. In an apparatus for measuring the periods of time of operation of any engine providing a source of pressure differential; a mechanism having an element rapidly movable in one direction to a set position and slowly movable in the opposite direction to an unset position; and valved means adapted for periodically connecting said mechanism to a source of pressure differential so as to cause rapid movement of the element to set position after each slow movement of the element to unset position. 40
